J. J. RYAN.

SNOW REMOVING MACHINE.

APPLICATION FILED JAN. 28, 1919.

1,310,546.

Patented July 22, 1919.

UNITED STATES PATENT OFFICE.

JOHN J. RYAN, OF BAYONNE, NEW JERSEY.

SNOW-REMOVING MACHINE.

1,310,546.

Specification of Letters Patent. Patented July 22, 1919.

Application filed January 28, 1919. Serial No. 273,612.

To all whom it may concern:

Be it known that I, JOHN J. RYAN, a citizen of the United States, and a resident of Bayonne, county of Hudson, State of 5 New Jersey, have invented new and useful Improvements in Snow-Removing Machines, of which the following is a specification.

This invention relates to machines for removing snow, comprising a tank vehicle 10 having an elevator at one end for raising the snow from the ground and depositing it into the tank, means for operating the elevator from the wheels of the vehicle, a snow receptacle located in the tank body and into 15 which the snow is deposited by the elevator and means for heating the receptacle to melt the snow; said receptacle having a valved spout at its lowest part from which the melted snow may be discharged into any 20 nearby sewer or other suitable place. An object of the invention is to insure proper action of the elevator when the machine is moving in curvilinear directions, as when passing around street corners, and to meet 25 such requirement the elevator is divided into two sections, each driven by a side wheel of the vehicle, whereby the speeds of the elevator sections will accord with variations of rotation of the inside and outside wheels 30 under such conditions.

A feature of the invention is the provision of means, as tappers acting on the bottoms of the elevators, to jar the snow from the buckets as they arrive in position to discharge the snow into the receptacle, the tappers of each section of the elevator being actuated in accordance with the speed of travel of the sections.

Another feature is an adjustable or yielding plow or device located in front of the mouth of the elevator for breaking up hard packed or incrusted snow. The mouth of the elevator is also provided with a yielding scoop, adapted to slip over any fixed 45 object or rigid obstruction in the path of travel of the machine, and also adapted to be raised and held away from the ground when the machine is traveling in inactive condition.

50 The tank body which is provided with the heating apparatus, preferably oil burners, and in which the snow receiving and melting receptacle is located will be suitably lined with fire brick or other non-heat 55 conducting material. It is also proposed to provide the melting receptacle with return

flues for the passage of the products of combustion of the burning oil from the burners to the chimney, thus insuring ample heating surface.

60 A snow removing machine embracing the above and other minor features is illustrated in the accompanying drawings, in which:

Figure 1, is a vertical longitudinal section on the line 1, 1, Fig. 2.

65 Fig. 2, is a plan view with the outside cover of the elevator removed.

Fig. 3 is a transverse section through the body and snow receptacle of the machine, and

70 Fig. 4, is a section of a portion of the elevator.

The machine may be operated by any suitable motive power; it is represented in the drawings as a trailer provided with rear 75 supporting wheels 5, 5, and supported at its front end on a tractor or motor truck 6, in the usual manner, as at 7. The body is a substantially rectangular tank 8, lined with fire brick or other heat resisting non-conducting material 9. At the rear end is secured the casing 10, of the snow elevator, which is suitably inclined and extends from 80 near the ground to the top of the body.

The elevator is longitudinally divided 85 into two parts 11 and 12, between which is a division 13, of the casing, the buckets of each part consisting of bottoms 14 and backs 15, are carried by a pair of chains 16, running over sprocket wheels on the shafts 17 90

and 18, which have bearings at the upper and lower ends of the casing. These shafts are in two parts, one for each of the sections 11 and 12 of the elevator, and the parts 17 95

are independently driven through the medium of chains and sprocket wheels 19, connecting their ends, which project from the sides of the casing, to the supporting and power wheels 5, respectively located at the same side of the machine. By this arrangement 100

undue strains on the elevator, operating to raise snow from the ground, in moving around street corners or making other curvilinear turns, will be avoided, as each set of elevator buckets will travel in accordance with the speed of rotation of its driving wheel and raise its proportionate amount of snow. The chain and sprocket 105

connections 19 may be provided with clutches 20, by means of which the parts 11 and 12 of the elevator may be set inactive when desired.

At the lower end of the elevator is an adjustable yielding scoop 21, shown as a cylindrical shell adapted to swing over the cylindrical end of the back plate of the elevator 5 casing 10, and carried by arms 22, fitted to rock on the projecting ends of the shaft 17. The scoop is held in position to scrape the snow from the ground and properly present it to the buckets by a spring 23, at each side 10 of the casing and bearing on a flat surface of the arm 22, in such manner as to give way to movements of the scoop, when it strikes an obstruction on the ground, and to return the scoop back to normal working position 15 after passing such obstructions. The flats on which the springs act are also so formed as to hold the scoop away from the ground when the machine is not in action and the scoop so raised by hand.

20 At times the snow, under some conditions, may by sticking to the buckets not be freely discharged therefrom at the top of the elevator, and to overcome this objectionable feature a suitable tapping or knocking device is provided for each set of buckets, consisting of hammers 24, extending from shafts 25, located between the runs of each section of the elevator and actuated by a toothed or notched wheel 26, secured to the 25 projecting end of the shafts 18, and acting on a tappet 27, secured to the end of each hammer shaft 25, the arrangement being such that the shafts 25 will be rocked and the hammers, preferably spring actuated, 30 will be caused to strike the undersides of the bottoms of the buckets several times during their transit past the hammers and so jar adhering snow from the buckets.

35 Ledges 28, as angle iron, secured to the outer walls 10 and the partition 13 of the elevator casing act as guides and supports for the buckets; see Fig. 4.

To break up snow which has become dense or hard by being packed or from other 40 causes a plow device is provided arranged in front of the mouth of the elevator. This device consists of prongs or teeth 29, secured to a bar 30, extending transversely under the tank body. These plow teeth yield to any 45 rigid obstruction they may strike. A suitable construction for this purpose is to carry the bar 30 by a parallel link system 31 at each side of the tank body, the bar 30 being connected to the horizontal rods of the 50 systems by side pieces 32. The weight of the bar and teeth may be sufficient to hold the teeth in proper working position, or a spring 55 may be used for this purpose. 33 designates a handle for raising the teeth from the ground when the machine is traveling out of action, and they be so held by any suitable locking device, as for instance a hooked catch 34.

The snow receiving and melting recepta-

cle 35, located in the tank body 8, has its 65 front and back walls and the lower part of its side walls inclined, the apex of which is provided with a spout 36, having a valve 37, through which the melted snow &c. may be discharged. A detachable pipe may be applied to this spout when it is desired to discharge the water &c. away from the side of the machine, as for instance if the machine be used to remove snow from car tracks, to allow the water to flow into a gutter or into 70 a culvert at the side of a street.

75 A suitable and preferred means for heating the snow in the receptacle is by the use of oil, a burner 38, for this purpose being located at the front of the machine and arranged to direct the burning oil into the chamber 39, formed by the horizontal wall 52, extending between the receptacle and the front wall of the tank body. Flues 40 extend through the snow receptacle fore and aft thereof. The products of combustion of the oil issuing from the burner 38 pass from the chamber 39, around the lower part of the receptacle and through the lower flues, if the flues be arranged in the lower part of 80 the receptacle, and into the rear chamber 41, then forwardly through the flues into the upper chamber 42 at the forward part of the machine, escaping therefrom through the chimney 43, which may be provided with an 85 ordinary damper device.

90 An oil tank 44, and an air tank 45, are carried on the top of the body 8; said air tank being supplied with air under adequate pressure by an air pump 46, whose motive power may be of any suitable character, as for instance it may be driven directly or indirectly by one of the supporting wheels of the machine. It is shown as driven from the top shaft 18 of the machine through the medium of a crank and rod connection 47.

95 A pipe 48 supplies oil from the tank 44 to the burner 38, and compressed air is supplied to the burner from the tank 45 by the pipe 49. These devices may be of ordinary 100 construction provided with regulating valves &c. and need no further description here.

105 A door 50, at the side of the combustion chamber 39, provides entrance to the chamber for cleaning and repairing purposes and for lighting the oil issuing from the burner and a door 51, at the side of the chamber 41, provides entrance to said chamber for cleaning and repairing purposes.

110 I claim:

115 1. A snow removing machine, comprising a tank vehicle, an elevator in two sections at one end of the tank body, rear supporting wheels at the sides of the machine and independent driving means connecting each section of the elevator to the wheel located at the same side of the machine, whereby the 120

operating speed of each section of the elevator is in accordance with its rate of travel over the ground.

2. A snow removing machine, comprising 5 a tank vehicle, an elevator in two sections at one end of the tank body, rear supporting wheels at the sides of the machine, independent driving means connecting each section of the elevator to the wheel located at the same 10 side of the machine, hammers arranged to act against the bottoms of the elevator buckets and means controlled by the elevators for actuating the hammers.

3. A snow removing machine, comprising 15 a tank vehicle, an elevator in two sections at the end of the tank body, rear supporting wheels at the sides of the machine, independent driving means connecting each section of the elevator to the wheel located at the same 20 side of the machine and a yielding scoop at the lower end of the elevator for presenting the snow to the two sections of the elevator.

4. A snow removing machine, comprising 25 a tank vehicle, an elevator in two sections at one end of the tank body, rear supporting wheels at the sides of the machine, independent driving means connecting each section 30 of the elevator to the wheel located at the same side of the machine, a yielding

scoop at the lower end of the elevator for presenting the snow to the two sections of the elevator and means for holding the scoop away from the ground.

5. A snow removing machine, comprising 35 a tank vehicle, an elevator in two sections at one end of the tank body, means for actuating each section of the elevator in accordance with its rate of travel over the ground, a snow receptacle located in the 40 tank body into which the snow is deposited from the elevator and means for heating the snow receptacle.

6. A snow removing machine, comprising 45 a tank vehicle, an elevator in two sections at one end of the tank body, rear supporting wheels at the sides of the machine, independent driving means connecting each section of the elevator to the wheel located at the same side of the machine and a yielding 50 plow device located in front of the mouth of the elevator adapted to break up hardened pieces of snow and other breakable obstructions.

Signed at New York, county and State of 55 New York, this 27th day of January, 1919.

JOHN J. RYAN.

In the presence of—

JOHN J. HAYDEN.
